UNITED STATES PATENT OFFICE.

JOHN V. FISHER, OF ATLANTIC CITY, NEW JERSEY.

ILLUMINATED DISPLAY FRAME.

Application filed September 26, 1925. Serial No. 58,862.

This invention relates to means for displaying advertising matter, so as to attract the attention of the public, and contemplates illuminating means and provision for the ready and convenient interchanging or replacement of the matter to be brought to the attention of the public.

The exhibitor embodies a display frame, such as ordinarily used, or of special construction, an illuminating box associated with the display frame and containing the lamps which shed rays of light to heighten the effect and make the matter stand out prominently and clearly so as to attract attention, and supporting and holding means for the sheet containing the matter to be displayed.

The invention is particularly designed for advertising moving picture products and exhibiting the photographs, lithographs and other matter furnished by the producers to call attention to the cast and scenes calculated to interest the public. Of course, the device is not restricted as to application and may be employed for display purposes generally.

While the drawings illustrate a preferred embodiment of the invention it is to be understood that in adapting the same to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is an elevational view of an illuminated display frame embodying the invention;

Figure 2 is a view similar to Figure 1, the members comprising the holder being swung into open position to expose the light box and illustrate the arrangement of the parts;

Figure 3 is an enlarged sectional detail view on the line 3—3 of Figure 1 looking in the direction of the arrows;

Figure 4 is an enlarged sectional detail view on the line 4—4 of Figure 1 looking to the left as designated by the arrows, and

Figure 5 is a detail sectional view showing a slight modification.

Corresponding and like parts are referred to in the following description and designated in the several views of the drawings by like reference characters.

The device comprises a supporting frame, a light box associated therewith and a holder for receiving the sheet containing advertising matter or the like to be displayed. The frame is designated by the numeral 1 and may be of the form usually provided for display purposes or may be specially constructed to meet any particular requirements. The frame may be constructed of any material and dimensions according to the specific use and particular design.

The light box associated with the frame 1 comprises a back 2 and enclosing sides 3 and is open at the front and disposed in the rear of the main frame 1 in line with the opening thereof. The light box may be constructed of any material and secured to the frame 1 in any preferred and substantial manner and when constructed of metal the enclosing sides 3 are extended laterally to form an outer flange 4 which is placed against the rear side of the main frame 1 to which it is attached by suitable fastenings 5. Electric lamps 6 or other preferred illuminators are arranged in the light box and are provided in sufficient number and suitably disposed to clearly light up the matter to be displayed.

Openings 7 are formed in opposite sides of the box 2 for ventilation and to prevent the rays of light from being projected beyond the sides of the device. Shields 8 project rearwardly from the frame 1 and are spaced from the sides of the light box an ample distance so as not to interfere with the free circulation of air. The shields 8 may form a part of the light box as indicated more clearly in Figure 3, or may be separate therefrom and secured to the frame 1 by fastenings 9 as indicated most clearly in Figure 5. Stops 10 project inwardly from the enclosing sides of the light box and limit the inward movement of the supporting member comprising the holder. The stops 10 preferably consist of portions partly cut from the sides 3 and pressed inwardly, as shown most clearly in Figure 3.

2

The holder comprises two complementary parts between which the sheet 20 bearing the matter to be displayed is confined. These parts consist of an inner supporting member and an outer retainer member, each being of similar or like formation. The inner supporting member comprises a frame 11 and a plate 12 preferably of glass or other material which will not obstruct the passage of light. This member is hinged to the main frame 1 to one side of the opening thereof, as indicated at 13, whereby the member may be swung to one side to permit ready access to the interior of the light box for any purpose. The stops 10 limit the inward movement of the supporting member and the latter is provided with a tab 14 for convenience of swinging the member into open position. The translucent plate 12 may be secured to the frame 11 in a manner to admit of its ready replacement and for this purpose a retaining strip 15 is movably held to the frame 11 by a pin and slot connection 16. The slot is inclined whereby movement of the strip 15 in one direction carries the strip out to clear the plate 12 and movement in the opposite direction carries the strip 15 inward to overlap and engage an edge portion of the plate 12. A lower strip 15' engages the lower end of the plate 12. The strips 15 and 15' are of angle formation and are attached to the frame 11 by suitable fastenings. The upper strip 15 is shown provided with two similarly inclined slots which receive the pins 16 carried by the frame 11 which, when closed, enters the opening of the main frame 1 and partly enters the open side of the light box 2, as shown in Figures 3 and 4. The strip 15 can be moved only when the frame 11 is swung outward to clear the main frame 1. Forward movement of the strip 15 causes the inclined slots therein to ride upon the pins 16 and in consequence the strip is carried upward and clears the glass 12 which may be removed or placed in position as desired. When the strip 15 is pushed rearward the inclined slots thereof ride on the pins 16, thus carrying the strip downward to a position to overlap the top of the glass 12 and hold it in place. The lower strip 15' is fixed and acts jointly with the strip 15 to retain the glass 12 in place, as shown most clearly in Figure 4.

The outer retainer member comprises a frame 17 and a translucent plate 18 which may be retained in place in any manner. The retainer member is hingedly connected to the frame 1 as indicated at 19, whereby it may be swung into open position, as indicated in Figure 2. The retainer member is adapted to overlie the supporting member and the frame 17 thereof is constructed to engage about the frame or a portion of the supporting member to confine the advertising sheet therebetween, as indicated most

clearly in Figures 3 and 4. The retainer member is provided with a suitable lock 21 for securing the holder when the members are closed, thereby preventing tampering with the device by unauthorized persons. 70

The part 1 constitutes the main support and is adapted to be positioned for observation in the usual way and in accordance with the present invention the sheet 20, containing the photographs, pictures and other matter to be displayed, is stretched over the inner supporting member of the holder and is confined thereto by the outer retainer member, the two members comprising the holder being made secure by means of the 80 lock 21. To heighten the effect and bring out the matter to be displayed in a way to engage the attention of the public, the lamps 6 are lighted and the rays of light projecting through the translucent plates 12 and 13 and the sheet 20 cause the matter to stand out in relief whereby the end sought to be effected is attained. The interior of the light box is coated with white enamel or may be otherwise coated so as to reflect light and 90 project the rays through the holder and the advertising sheet carried thereby. 90

Having thus described the invention, I claim:

1. A display device comprising a main frame having a display opening, a light box carried by the said frame and disposed opposite and in the rear of the said display opening, a supporting member hinged to the main frame to swing outwardly and comprising a frame and a translucent plate, a display sheet extended over the supporting member, and a retainer member hinged to the main frame to swing outwardly and adapted to confine the display sheet between the supporting and retainer members. 105

2. A display device comprising a main frame having a display opening, a light box carried by the said frame and disposed opposite and in the rear of the said display opening, a supporting member hinged to the main frame and occupying the display opening thereof and the front portion of the light box, a display sheet extended over the supporting member, and a retainer member hinged to the main frame and closing against the front thereof and adapted to confine the display sheet between the said supporting and retainer members. 110

3. A display device comprising a light box having an open front and openings in opposite sides, a display sheet extended across the open front of the box, and shields at opposite sides of the box to restrict the rays of light projected through the openings thereof. 120

4. A display device comprising a main frame having a display opening, a light box carried by the said frame and disposed opposite and in the rear of the said display 130

opening, a supporting member hinged to the main frame and occupying the display opening thereof and the front portion of the light box, stop means for limiting the closing of the supporting member, a display sheet extended over the supporting member, and a retainer member hinged to the main frame and closing thereagainst and adapted to confine the display sheet on the said supporting member, both the supporting and retainer members consisting of a frame and a translucent plate.

In testimony whereof I affix my signature.
JOHN V. FISHER. [L.S.]
